UNITED STATES PATENT OFFICE

2,521,324

CRANE TROLLEY

Harvey W. Ball, Alliance, Ohio, assignor to The Morgan Engineering Company, Alliance, Ohio, a corporation of Ohio

Application May 11, 1948, Serial No. 26,380

2 Claims. (Cl. 212—20)

1

This invention relates to improvements in crane trolleys or the like, and more particularly to trolleys used with a scarfing yard crane.

A crane of this type has utility in handling slabs which have been rolled by a blooming or slabbing mill. The slabs are usually removed from the slabbing mill run-out table by an overhead crane, and subsequently distributed in a so-called chipping or scarfing yard, where the imperfections are either chipped or scarfed out of the slabs. As it may be necessary to perform this operation on both sides of the slabs, a magnet crane is employed to turn the slabs over so that both sides can be made available to the chippers and scarfers. When the slabs have been treated, the magnet crane picks them up and stacks them for removal to the continuous mill. As the treatment or processing in the chipping or scarfing yard is of a continuous nature, it will be readily appreciated that a fast operating crane should be employed.

The primary object of the present invention is to provide the trolley with improved means functioning as a counterweight for the lifting magnets or other lifting means of the trolley, the parts being so geared together that the counterweight moves upwardly when the magnets move downwardly, and vice versa, and the counterweight stem and rack are of such length relatively to the magnet stem and its rack that the latter travels approximately twice as far in either direction as the counterweight stem, in one revolution of the motor which controls the up and down movements of the magnets. In keeping with the invention, the counterweight with its stem, and the magnet stem, together with its magnets, weigh about the same, but difference in leverage in the gearing, produces an unbalanced condition between the magnet and its stem and the counterweight and its stem, sufficient to allow the magnet stem to lower by gravity alone or by use of a motor. In other words, the weight of the magnet stem with its magnets is sufficient to turn the gearing and the motor, when the conventional magnetic brakes are released to allow the magnets to be lowered onto the work. If the gearing actuating the magnet stem rack were the same as that actuating the counterweight rack, the latter would travel the same distance as the magnet rack, but this condition is undesirable as it would allow the counterweight stem to project downwardly and possibly engage material stored or stacked in the yard when the magnet stem is in the highest position. If the initial position

2

of the counterweight stem was arranged higher on the trolley a top-heavy structure would be provided.

Accordingly, another object of my invention is to so proportion and arrange the gearing, stems and racks as to make the counterweight rack travel about $\frac{1}{2}$ as far as the magnet rack, and to have the counterweight weigh approximately the same as the magnet stem and rack with its magnets. As the slabs to be handled are not very heavy compared with the unbalanced weight of the two racks and their loads, the handling of the slabs can be easily accomplished if the weight of the magnet rack is partly balanced by the counterweight rack.

In further explanation, if the counterweight, rack and stem have a dead weight of 16,000 lbs., which is the same as the dead weight of the magnets, rack and stem, and the counterweight rack moves only $\frac{1}{2}$ as far in one direction as the magnet rack does in the opposite direction, the balancing effect of the counterweight is cut in half, so that it exerts about 8,000 lbs., balancing effort against the 16,000 lbs. of the magnet.

The invention is illustrated in the accompanying drawings, in which:

Fig. 1 is a diagrammatic top plan view of a crane bridge and the trolley which travels thereon, the bridge being mounted on portions of the bridge supporting tracks.

Fig. 2 is a diagrammatic side elevation of the same, and showing a vertical section of a side wall of the yard in which the crane operates.

Fig. 3 is a side elevation of essential parts, mounted on the trolley, for actuating the stems of the magnets and counterweight.

Fig. 4 is a side elevation of the trolley with certain parts removed to facilitate illustration.

Fig. 5 is a top plan view of the trolley shown in Fig. 4, and with the counterweight stem illustrated in horizontal section.

Referring to the drawings, 6 designates a side wall of a chipping or scarfing yard, and 6a indicates the floor thereof. Rails 7, 7a are mounted respectively on the wall and floor, to support the wheels 8 of the crane bridge 9, having rails (not shown) for the wheels 10 of a trolley 11. The parts 6 to 11, inclusive, are shown more or less diagrammatically to illustrate the environment of the present invention, and those skilled in the art will appreciate the fact that various arrangements may be used, and understand that the crane bridge 9 is propelled along the tracks 7, by conventional means (not shown), and the trolley 11 is propelled lengthwise of the bridge by the usual means.

In accordance with the invention, an electric motor 12, is mounted on the chassis 13 of the trolley, and the driving shaft 14 of the motor is connected at one end by a flexible coupling 15, to the shaft 16 of a worm reduction gear 17. The ends of the motor shaft and reduction gear, remote from the coupling 15, are connected with magnetic brakes 18, diagrammatically illustrated, and which may be of the general type disclosed in the Neenan patent, No. 891,632. In that type of brake, the brake shoe or shoes, are applied by spring pressure and released by electrical energy, so such brakes may be electrically connected to the conventional control means (not shown) of the motor 12, whereby during control of the motor, the spring loaded brakes will be applied or released, when necessary.

In keeping with the invention, the reduction-gear mechanism 17 drives a horizontal shaft 19, to which is keyed a pinion 20, meshing with gears 21 and 22, preferably of the same size. The gear 21 is keyed to a horizontal shaft 23, and the gear 22 is fixed to a parallel shaft 24. Shaft 23 has fixed thereto, a relatively large pinion 25, while shaft 24 is fixed to a relatively small pinion 26. Of course, the shafts 19, 23 and 24 are mounted in suitable bearings on the chassis, one of said bearings being indicated at 27, in Fig. 4.

Conventional magnets or lifting means 28 are carried by the trolley, and depend from a vertically movable stem 29, guided by guide rolls 30, rotatably arranged on the chassis. A counterweight 31 is mounted on another vertically movable stem 32, guided by rolls 33, also mounted on the chassis.

In accordance with the present invention, the stems are interconnected or geared to one another, and the stem 32 is about half the length of the stem 29; the stems being so connected that they move in opposite directions. This may be accomplished by providing the stem 29 with a toothed rack 34, meshing with the pinion 25, and providing the stem 32 with a toothed rack 35, meshing with the pinion 26. As the stem 29, with its magnets and rack, weigh approximately the same as the stem 32 with the counterweight and its rack, when the motor 12 is de-energized, the stem 29 can move downwardly by gravity, from the position shown in Fig. 4, until the magnets 28 engage the slab to be lifted. Such descent of the magnets in spite of the counterweight, is brought about, due to the difference in ratio between the pinions 25 and 26.

To more clearly explain the operation of the trolley, assume that the crane is going to pick up a slab and convey it to another point. Assume also that the magnets are in the elevated position shown in Fig. 4, so that the magnets and their stem will not be obstructed by obstacles within the chipping or scarfing yard. In order to lower the magnets and engage the slab, the operator moves his control lever (not shown) to lowering position. This accomplishes two results; it energizes the magnetic brakes 18, to release the brakes, and at the same time, it leaves the motor and worm gear unit free to operate. Brake release takes place instantly, and as the motor 12 is energized at the same time, the motor plus gravity will move the magnets in a downward direction onto the slab, whereupon the magnets, which are energized, engage the slab, and the control lever is reversed, causing the slab to be hoisted until it is free of the floor surface. The control lever is then moved to neutral position, which stops the motor and de-

energizes the magnetic brakes. As the latter are spring loaded, they immediately grab the brake wheels and hold the slab load in suspension, ready to be moved elsewhere by travel of the trolley 11, or of the bridge 9, or both.

If the gearing actuating the magnet rack were the same as that actuating the counterweight rack, the latter would travel the same distance as the magnet rack, but this condition is not permissible in a structure of the character which I have improved, as it will allow the counterweight to engage articles stored in the yard when the magnet rack is in its highest position, and the counterweight, when in its highest position, would result in a top-heavy structural condition. Therefore, I have so proportioned the gears with reference to one another as to make travel of the counterweight rack about $\frac{1}{2}$ the distance of the travel of the magnet rack, and have the counteracting parts of about the same weight. The unbalanced condition of the two racks does not provide any serious disadvantages during lifting of loads and provides the advantage of facilitating the lowering of the stem 29. In addition the balancing arrangement is intimately tied into the operating mechanism in a compact and serviceable manner, in comparison with the usual orthodox means previously employed, such as levers, sheaves, cables, and swaying counterweights, all of which would be hard to maintain in a fast-operating crane.

While I have disclosed what I deem to be a preferred form of my apparatus, I do not wish to be limited thereto, as there might obviously be changes made in the form, construction, and arrangement of the constituent elements, as well as the modus operandi, without departing from the spirit of the invention, as comprehended within the scope of the appended claims.

What I claim and desire to secure by Letters Patent is:

1. In a crane trolley, or the like, a lifting means, a toothed rack operatively connected to said lifting means, a counterweight, a second toothed rack operatively connected to the counterweight for raising and lowering the latter, a drive shaft mounted on the trolley, a prime mover mounted on the trolley and driving the drive shaft, a pinion fixed to the drive shaft, first and second driven shafts, gears of the same size fixed to each of the driven shafts and meshing with the first-mentioned pinion, a relatively large pinion fixed to the first driven shaft and meshing with the first-mentioned toothed rack, a relatively smaller pinion fixed to the second driven shaft and meshing with the second toothed rack, the gearing being so arranged as to cause the second rack to move in one direction when the first-mentioned rack moves in the opposite direction and vice versa, the pinions on the driven shafts being of such relative ratio as to cause the second rack to travel in one direction about $\frac{1}{2}$ as far as the first-mentioned rack when the latter moves in the opposite direction.

2. In a crane, a trolley, load-lifting means including a vertically disposed stem arranged for up and down movements relative to the trolley, an elongated vertically disposed counterweight of less length than said stem arranged for up and down movements relative to said trolley, a driven shaft, a second driven shaft, a drive shaft arranged intermediate said driven shafts, a gear wheel carried by the first driven shaft, a gear wheel carried by the second driven shaft, a pinion

fixed to said drive shaft meshing with said gear wheels, means for rotating the drive shaft to turn the driven shafts in opposite directions, rack gear teeth carried by the stem, a pinion secured to the first driven shaft meshing with said rack gear teeth, rack gear teeth carried by the counterweight, a pinion secured to the second driven shaft and meshing with the rack gear teeth carried by the counterweight, the gearing between the drive shaft and the counterweight and the gearing between the drive shaft and the stem being of such relative ratio as to cause the stem to move a greater distance than that of the

counterweight during one revolution of the drive shaft.
